UNITED STATES PATENT OFFICE

FRANCIS C. BRANDENBURG, OF PIQUA, OHIO, ASSIGNOR TO THE WOOD SHOVEL AND TOOL COMPANY, OF PIQUA, OHIO, A CORPORATION OF OHIO

METHOD AND APPARATUS FOR BENDING WOOD

Application filed September 1, 1927, Serial No. 216,912. Renewed January 18, 1932.

This invention relates to bending wood; e. g., wooden handles for shovels. A very large proportion of shovel handles require a reverse-curve bend at the end which attaches to the blade of the shovel, and a constantly increasing number of these handles require an additional bending operation at the other end, whereby a fork is formed to receive a handle grip. For many years the most satisfactory method known for bending these handles has been that of boiling or steaming them and then pushing them endwise into forms having the curvature it was desired to impart to the handles, and leaving them in the forms until the wood dried. To permit removal of the handles from them, the forms have consisted of planar channels having the required lateral curvature, and the handles were removed at the open side of the channels. These forms were made of cast or malleable iron. A serious objection to this method lay in the large percentage of loss through the handles breaking, or the wood being so badly cracked or splintered as to make the handles useless, or at least reduce them to the grade of "seconds." Another difficulty has been the staining of many of the handles through some chemical action between the wet wood and metal forms. Removal of this stain was expensive, and it was not always possible to remove it.

After long experimentation, and trial of different kinds of forms, I found that by using a substantially tubular form a large reduction in the percentage of loss through breakage, cracking and splintering was effected. But I found the discoloration of the wood increased, due to the fact that drying of the wood was retarded by its more nearly complete investment, necessitating longer retention in the forms. I therefore set about finding a preventive for this staining of the wood, and found coating the forms with tin put a stop to the trouble. But I also found that tinning the forms effected a very considerable further reduction in the loss through breakage, cracking or splintering. I cannot fully explain this, but it is probable that this unexpected result is at least partly due to reduced friction: the handles slide into tinned

forms easily and noiselessly, while considerable groaning and chattering accompanies their entrance into untinned forms. Possibly this chattering has a disintegrative effect on the wood, and that its elimination reduces the loss I have referred to.

I shall now proceed to describe the preferred embodiment of my invention, and its operation, with the aid of the accompanying drawings, in which,

Fig. 1 shows a bent-wood shovel handle, of what is known as the split D type. It is to be understood that in practice the fork at the left hand end of this figure does not lie in the same plane as the bend in the right hand end, but it lies in a plane perpendicular to the right hand end so that when the handle is put on a shovel the fork will lie in a plane parallel to the shovel blade;

Fig. 2 shows the handle as it appears before being bent to the form shown in Fig. 1;

Fig. 3 illustrates the form for bending the right hand end of the handle shown in Fig. 1;

Fig. 4 illustrates the form for bending the tines of the forked end of the handle shown in Fig. 1;

Fig. 5 is an elevational view of the machine for pushing the handles into the forms. In this view the machine is equipped with the form shown in Fig. 3, preparatory to bending the right hand end of the handle shown in Fig. 1;

Fig. 6 is a plan of the jig for supporting the form shown in Fig. 3, showing the form in place;

Fig. 7 is an elevation of the jig shown in Fig. 6; and

Fig. 8 is a plan of a portion of the machine shown in Fig. 5.

The form for bending the lower end of the handle, the end shown at the right hand in Fig. 1, is well illustrated in Fig. 3, and comprises members 25 and 26, so connected at 27 by a hinge that the members can be separated, as is indicated with dotted lines. Each of these members is semi-annular in cross section, so when the members are together, as in Fig. 3, they form substantially a tube. One end of this tube is obstructed by the hinge, but the other end is open. The handles are

bent, after having been steamed or boiled to make them pliable, by forcing them endwise into the tube through the open end. The members 25 and 26 are held together with U shaped clamp, the ends of which are seen at 28—28 in Fig. 3. The clamp is left on the form and the form on the handle until the wood dries, which requires about forty-eight hours. The clamp is then knocked off and the members swung apart to release the handle. The longitudinal curvature of the members 25 and 26, and therefore of the form as a whole, is appropriately similar to the curvature to be imparted to the handle. That is, the curvature is enough different from that desired in the handle, so the handle will have the desired curvature after it springs back a little upon being released from the form.

Referring now to Fig. 5, I shall describe the machine for bending these handles. As this machine is of a well known and commonly used type, it will suffice to say it comprises a bed plate 30 mounted on suitable legs 31. Slidably mounted upon the bed is what I shall call a pusher, for want of a better name. This is indicated by the numeral 32, and at one end the pusher carries a roller 33. Suitably journaled on the bed is a shaft 34, which carries a cam 35 adapted to bear on the roller 33 and move the pusher in one direction. The shaft is rotated through suitable speed-reducing gearing by a belt, not shown, which runs on a pulley 36. Obviously, the shaft may be rotated by other means, if desired. The pusher is retracted by a weight, not shown, but other means may be employed to do this. The bending form lies in a jig, comprising a plate 42 bolted to the bed 30 and having guide lugs 37, and an abutment 38 which receives the thrust as the handle is pushed into the form. See also Figs. 6 and 7. At 39 a recess is formed in the plate 42 to accommodate one leg of the clamp 28 which holds the form closed. See also Fig. 3. Having laid a form in the jig, the operator holds the steamed end of the handle 41 in the mouth of the form, with the other end of the handle in the path of the block 40 which is adjustably fastened to the pusher 32. As the pusher comes forward, moved by the cam 35, the block 40 impinges on the end of the handle and forces the handle into the form. Preferably the machine is kept running and the shaft 34 driven at such velocity that after the pusher recedes, under the action of the weight before mentioned, the operator has time enough to remove the handle, to put a new form in the jig and get a new handle into place by the time the cam begins to move the pusher forward again.

It will be observed that the member 25 of the form lies on one side, and the member 26 on the opposite side of the neutral surface of the handle 41. It follows that the mem-

bers 25 and 26, whose circular cross section has about the same radius as that of the handle, invest the handle, giving support to its fibres during the time the fibres are subject to great strain tending to separate them from one another. This will be better understood if one will consider the destructive or disintegrative effect of bending a round handle by forcing it endwise into a sinuous channel the walls of which are parallel to the neutral surface of the handle as the handle assumes the sinuous form imparted by the walls of the channel; in other words, wherein the walls are tangent to the circular cross section of the handle. The contacts of the handle with the walls of such a channel are mere lines on opposite sides of the axis of the handle, and whatever bending moment is imparted to the remaining parts of the handle can only be such as is transmitted through that (whatever it is) which binds the fibres of the wood together. It is because in the past handles have been bent in forms of this kind that the loss through breakage has been so great. In my tubular or investing forms bending moment is applied directly to the major part of the handle surface and thus this severe strain on the integrating elements of the wood is eliminated. This has resulted in a large reduction in the breakage or splintering of the wood. While the form may be arranged to completely surround the handle I prefer to provide for a narrow space between the contiguous edges of the members 25 and 26, as in Fig. 3. This serves to ventilate the handle and facilitate its drying. On the other hand, the lack of complete investment or enclosure of the handle is immaterial, since the open space is near the neutral surface, where the strain on the wood is comparatively slight.

While the forms may be made of other materials I prefer to make them of cast iron. While cast iron stains the handles, I have found that by tinning the iron this difficulty is eliminated. The forms might be made entirely of tin, but to get sufficient strength they would need to be much thicker, and they would then be heavy and clumsy to handle. Moreover, the cost would be prohibitive. It is not necessary to describe the method of tinning the iron as the practice of coating iron with tin is very old and the manner of doing it is well understood by many persons. It is quite common to tin articles made of cast or malleable iron, where they may be subjected to conditions which would cause them to rust. For example, the metal parts of ice cream freezers are commonly tinned; also of refrigerators.

Referring now to Fig. 4 I shall describe the form for bending the tines of the fork at the left hand end of the handle shown in Fig. 1. At a glance it will be seen that this form is in effect two forms of the type shown in Fig. 3, enabling the two tines to be bent

simultaneously. This form contains a central member 50, of skeleton-like formation, having the general form of a wedge. That is, it has a thin end 51 and thick end 52, similar to a wedge. It differs from an ordinary wedge in that its sides have the reverse curvature which it is desired to impart to the tines of the fork. As is indicated by the sectional insert, in Fig. 4, the transverse lines 5 of the wedge are straight, being made so because the transverse lines of the inner surfaces of the tines are straight. Referring 10 to Fig. 2 it will be seen that the tines 53 are produced by making a saw cut 54 down the center of the turned staff or handle 41. The 15 annular groove 55 near the end is merely a provision for securing the grip to the tines and is not concerned with the present invention. Apposed to each side of the wedge-like member 50 is a form member 56, each of 20 which is attached to the thick end of the wedge by a hinge 57. In cross section the members 56, at least their inner portions, are semi-circular. In fact, these members are 25 substantially the same in cross section as the members 25 and 26.

Referring now to Fig. 8, it will be seen that the bending machine is there fitted with a jig 30 adapted to receive the tine-bending forms. This jig comprises a plate 60, upon which is a boss 61 having the contour of the central opening 62 in the wedge 50, shown in Fig. 4. The form is laid on the plate with the boss 61 in the opening 62 in the wedge and thus the 35 form is anchored to the plate while the tines are pressed into the form. The plate 60 is bolted to the bed 30 of the machine in place of the plate 42 previously described. This plate is provided with a recess 63 to receive a 40 U shaped clamp 64, which clamp is set in the recess before the bending form is put in place, with the legs of the clamp pointed upward. The purpose of this clamp is to connect the free ends of the members 56 and hold 45 them a predetermined distance apart, while permitting the members to move laterally with reference to the thin edge of the wedge. The operator holds the slotted end of the handle 41 in the mouth of the form, with the slot 50 parallel to the thin end of the wedge, until the block 40 on the pusher 32 impinges on the other end of the handle. The pusher then forces the handle into the form. The edge 51 of the wedge separates the tines 53—53, 55 one tine entering the space between one member 56 and the wedge, the other tine entering the space between the other member 56 and the wedge. The form and handle are then lifted out of the machine as a unit and the 60 form is left on the handle until the wood dries, after which the clamp 64 is knocked off and the form removed.

While it is intended to cut the slot 54 in the center of the handle, the cut is sometimes 65 slightly off-center. In such cases freedom of

the members 56—56 to move laterally as a unit with reference to the point of the wedge, permits automatic adjustment of the relative sizes of the spaces into which the tines are entering, appropriate to the unequal thickness of the tines. This prevents excessive strain on either tine, with resulting elimination of breakage which might otherwise occur. This self-accommodation of the form 70 also takes care of cases where the pliability of the tines is unequal because of some inequality in the wood, its grain, etc. These forms are made of cast iron, and tinned for the same reasons as I tin the forms 25—26, and in both cases the resulting reduction in 75 friction effects a considerable reduction in loss from breakage of handles. Friction is caused partly by adhesion of the parts and partly by their roughness. As the chattering, 80 which I have previously described, is due in untinned forms to the intermittent adhesion, sticking, of the wood and iron, and as tinning the forms eliminates the chattering, it is plain that there is much less adhesion 85 between the wood and tin than between the wood and iron. Where both ends of the 90 handle are bent, as in Fig. 1, instead of using the block 40 and having it bear on the end already bent in bending the other end, I have found it desirable to mount a vice on the pusher, in which to clamp the handle intermediate 95 its ends. As this is not claimed as part of my invention it is unnecessary to illustrate it.

As I have previously stated, the loss 100 through splintering or breakage of the wood was very high while using the old method. In bending the tines of split D handles the loss has sometimes run as high as thirty per cent of the handles bent. With my tubular forms, coated with tin, the loss varies from 105 three to twelve percent of the handles bent.

It is not to be understood that my invention is limited in its scope to the particular 110 embodiments shown, the scope of the invention being limited only by my claims, which are as follows:

1. A form for bending wood, comprising two members having a curvature appropriately similar to the curvature to be imparted to the wood, said members being situated in apposition with a space between them sufficient to admit the piece of wood to be bent, the surfaces upon which the wood slides as it is pushed into the form being composed of metal between which and the wood there is much less adhesion than there would be between cast iron and the wood. 115

2. A form for bending wood, comprising two members having a curvature appropriately similar to the curvature to be imparted to the wood, said members being situated in apposition with a space between them sufficient to admit the piece of wood to be bent, the surfaces upon which the wood slides as 120 125 130 135 140 145 150 155 160 165 170 175 180 185 190 195 200 205 210 215 220 225 230 235 240 it is pushed into the form being composed of tin.

3. A form for bending wood, comprising a tube composed of sections, and means enabling the sections to be separated sufficiently to remove the bent wood therefrom, the surfaces of the tube upon which the wood slides as it is pushed thereinto being composed of metal between which and the wood there is much less adhesion than there would be between cast iron and the wood.

4. A form for bending wood, comprising a tube composed of united sections, and means enabling the sections to be separated sufficiently to remove the bent wood therefrom, the surface upon which the wood slides as it is pushed into the form being composed of metal between which and the wood there is much less adhesion than there would be between cast iron and the wood and which will not stain the wood.

5. A form for simultaneously bending both halves of a slotted wooden shaft to produce the fork of a split D handle, said form comprising a wedge, each side whereof has the curvature which is to be imparted to the tines of the fork; a member on each side of said wedge having a curvature complementary to the aforesaid curvature of the adjacent wedge-side and spaced therefrom a sufficient distance to admit one tine of the fork, and means connecting said members and keeping them a predetermined distance apart, which means permits the members to move laterally as a unit with reference to the thin end of the wedge while the tines are being pushed into the form.

6. A form for simultaneously bending both halves of a slotted wooden shaft to produce the fork of a split D handle, said form comprising a wedge, each side whereof has the curvature which is to be imparted to the tines of said fork; a member on each side of said wedge having a curvature complementary to that of the adjacent wedge-side and spaced from said side a sufficient distance to admit one of said tines, the ends of said members contiguous to the broad end of the wedge being maintained at the required distance therefrom by hinges which permit the members to swing outward for releasing the fork after it has become set to the form, and means connecting the free ends of said members and keeping them a predetermined distance apart, while leaving them free to move laterally as a unit with reference to the thin end of the wedge.

7. A form for simultaneously bending both halves of a slotted wooden shaft to produce the fork of a split D handle, said form comprising a wedge, each side whereof has the curvature which is to be imparted to the tines of the fork; a member on each side of said wedge having a curvature complementary to the aforesaid curvature of the adjacent

wedge-side and spaced therefrom a sufficient distance to admit one tine of the fork, each of said members combined with the contiguous wedge side forming a tube having a cross-section substantially like that of the tine to be bent therein, and means connecting said members and keeping them a predetermined distance apart, which means permits the members to move laterally as a unit with reference to the thin end of the wedge while the tines are being pushed into the form.

8. A form for simultaneously bending both halves of a slotted wooden shaft to produce the fork of a split D handle, comprising two passages, each having a curvature substantially such as is to be imparted to the tines of said fork, said passages being so disposed, relative to each other, that said halves of the shaft can be pushed endwise into said passages simultaneously, one half entering each passage, said form being made of metal coated with tin, whereby to make movement of the wood in said passages comparatively free from friction.

9. A form for simultaneously bending both halves of a slotted wooden shaft to produce the fork of a split D handle, said form comprising a wedge, each side whereof has the curvature which is to be imparted to the tines of the fork; a member on each side of said wedge having a curvature complementary to the aforesaid curvature of the adjacent wedge-side and spaced therefrom a sufficient distance to admit one tine of the fork, and means connecting said members and keeping them a predetermined distance apart, which means permits the members to move laterally as a unit with reference to the thin end of the wedge while the tines are being pushed into the form, the surfaces on which the wood slides as it is pushed into the form being composed of metal between which and the wood there is much less adhesion than there would be between cast iron and the wood.

10. A form for simultaneously bending both halves of a slotted wooden shaft to produce the fork of a split D handle, said form comprising a wedge, each side whereof has the curvature which is to be imparted to the tines of the fork; a member on each side of said wedge having a curvature complementary to the aforesaid curvature of the adjacent wedge-side and spaced therefrom a sufficient distance to admit one tine of the fork, and means connecting said members and keeping them a predetermined distance apart, which means permits the members to move laterally as a unit with reference to the thin end of the wedge while the tines are being pushed into the form, the surfaces on which the wood slides as it is pushed into the form being composed of tin.

11. A form for simultaneously bending both halves of a slotted shaft to produce the fork of a split D handle, comprising two

5   passages, each having a curvature substantially such as is to be imparted to the tines of the fork, said passages being so disposed, relative to each other, that said halves of the shaft can be pushed into the passages simultaneously, one half entering each passage, the surfaces of said form upon which the wood bears as it slides thereinto being made of metal between which and the wood there is
10   very little adhesion.

10   12. The method of bending wood, which comprises pressing the wood endwise into a form having substantially the curvature to be imparted to the wood, which form invests the wood, thereby imparting bending moment directly to the parts of the wood which otherwise would undergo severe disintegrative strain, making the portions of the form on which the wood slides of tin.

20   13. The method of bending wood which comprises pressing the wood endwise into a form having substantially the curvature to be imparted to the wood, which form invests the wood, thereby imparting bending moment directly to the parts of the wood which otherwise would undergo severe disintegrative strains, making the portions of the form on which the wood slides of a metal that offers very low resistance to the sliding of the wood.

30   14. The method of bending wood which comprises pressing the wood endwise into a form having substantially the curvature to be imparted to the wood, making the portions of the form on which the wood slides of a metal that offers very low resistance to the sliding of the wood.
